UNITED STATES PATENT OFFICE.

JACOB W. LATTIG, OF GLENSIDE, PENNSYLVANIA, AND CHARLES L. GOODRUM, OF NEW YORK, N. Y., ASSIGNORS TO WESTERN ELECTRIC COMPANY, INCORPORATED, OF NEW YORK, N. Y., A CORPORATION OF NEW YORK.

PREPAYMENT COIN DEVICE.

1,241,998.

Specification of Letters Patent.

Patented Oct. 2, 1917.

Application filed April 25, 1916. Serial No. 93,387.

To all whom it may concern:

Be it known that we, JACOB W. LATTIG and CHARLES L. GOODRUM, citizens of the United States, residing at Glenside, in the 5 county of Montgomery and State of Pennsylvania, and at New York, in the county of New York and State of New York, respectively, have invented certain new and useful Improvements in Prepayment Coin 10 Devices, of which the following is a full, clear, concise, and exact description.

This invention relates to coin collecting devices for telephone pay stations.

The object of this invention is the provision 15 of a coin collecting device of the prepayment type in which calls may be stored for future use upon the deposit of a coin greater in value than the charge of a single call.

20 In accordance with this invention, means are provided whereby a metering mechanism may be manually set in an advanced position upon the deposit of a coin, said position depending upon the denomination 25 of the coin deposited. Means are provided for automatically restoring said metering mechanism step by step to normal position as the stored calls are consumed.

The invention is illustrated in the accompanying drawing, in which Figure 1 is a 30 perspective view partially in section of a coin collecting device embodying the features thereof, and Fig. 2 is a detailed perspective view partially in section of a locking mechanism for part of the apparatus 35 shown in Fig. 1.

The coin collecting device shown in the drawing comprises a cylindrical case 1 having a base member 2, the interior of said 40 casing being divided into an upper and lower compartment by means of a partitioning member 3. Journaled in the base 2 and partitioning member 3 is a shaft 4, carrying at its upper end a conical shaped drum 5. 45 A spiral spring 6 having one of its ends attached to a post set in the partitioning member 3 and its other end secured to the shaft 4, functions to restore said shaft to normal position. Staggeredly mounted upon the 50 surface of the drum 5 are a plurality of pins 7 having their respective positions deter-

mined by the size of the coin they are intended to engage. On the top of the casing 1 is a knurled nut 8 having a reduced portion, which projects through an aperture in 55 said casing and has secured thereto a circular disk 9. The disk 9 carries a coin chute 10 formed of a pair of wing members bent at right angles to the surface of said disk. A normal stop pin 11 functions to place the 60 chute 10 in alinement with a slot 12 made in the casing 1, which slot is large enough to accommodate any size coin.

A sleeve 13, placed upon the lower end of the shaft 4, is provided with a shoulder 65 which supports an escape wheel 14 loosely mounted thereon. Adjacent the escape wheel 14 is placed a washer 15 and mounted intermediate said washer and a collar 16, secured to the shaft 4 and provided with an 70 arm carrying a spring actuated pawl 17, is a ratchet wheel 18. A spring pressed pawl 19 fastened to the escape wheel 14 cooperates with the ratchet wheel 18 to hold the same in an advanced position when rotated 75 in a manner hereinafter to be described. A pawl-stop member 20 normally holds the pawl out of engagement with the ratchet wheel 18. The sleeve 13 is rotated in a counter-clockwise direction by means of a 80 spiral spring 21 having one of its ends anchored to a post set in the base 2 and its other end secured to the sleeve itself. A pin 22 having its end tipped with an insulating material projects from the sleeve 13 in 85 a manner to control a pair of contact springs 23 suitably supported from the base 2. The contact springs 23 are adapted to control the transmission circuit of a subscriber's substation, and are held apart when the above described mechanism is in normal position, thereby disabling the substation. 90 Electromagnet 35 controls an armature 36 carrying a set of escape pallets 37 adapted to cooperate with the escape wheel 14 so that each 95 time the electromagnet is energized the escape wheel 14 is adapted to be released one step. The winding of the electromagnet 35 is included in a subscriber's line circuit and may be actuated by a central office operator. 100 The inclusion of the electromagnet 35 and the contact springs 23 in the subscriber's

line circuit will be apparent from the drawing without describing the same. A cash box 26 is attached to one side of the casing 1 and has communication therewith by means 5 of a slot through which the inserted coins are caused to fall, as will hereinafter be set forth. Immediately in front of the opening into the cash box is a bell crank lever 40 pivotally mounted in the base 3, having one 10 of its ends bifurcated in such a manner as to constitute a pawl 41 and a stop pin 42, both of which elements control the movement of the drum 5, as will hereinafter be more fully explained. The long arm 43 of 15 the lever is actuated by the weight of a coin falling into the till 26. A spring member 44 engaging a pin carried by the lever 40, maintains said lever in either of its actuated positions. In order to restore lever 40 to 20 its normal position, after having been actuated by the weight of a coin, a wedge-shaped projection or lug 45 is provided on the drum 5, this lug being so located as to engage the stop pin 42 upon the drum being 25 returned to its initial position and thereby cause the restoring of lever 40 against the pressure of the spring 44.

The operation of the above described mechanism is as follows: Assume that a 30 twenty-five cent piece has been inserted into a slot 12. It will be retained in a given position by the chute 10, and, by turning the nut 8, the disk 9 will be rotated in a clockwise direction until the periphery of the 35 coin engages one of the pins 7, which, as stated before, will be individual to the respective coins of various denominations. By the coin engaging the pin 7, a locking means is formed for rotating the drum, 5 which 40 may now be advanced by continuing the rotation of the nut 8. It may be mentioned here that the drum 5 will be prevented from returning to normal position until it has reached the limit of its travel, because of 45 the pawl 41 engaging the teeth formed on the lower periphery of said drum. This feature eliminates the possibility of fraud which might otherwise be practised as will be apparent hereinafter. When the drum 5 50 has been rotated sufficiently to bring the deposited coin in front of the opening into the coin box 26, it will fall therein, thus releasing said drum and allowing it to restore to normal position under the tension 55 of the spring 7.

It will be noted that during the rotation of the drum 5, the pawl 17 engaging the ratchet wheel 18, advances the same five units in a clockwise direction. This operation places the spiral spring 21 under tension which causes the teeth of the escape wheel 14 to be pressed against one of the escape pallets 37. It will also be noted that 60 the contact springs 23 are now closed, thus 65 enabling the calling subscriber to signal the

central office. The call having been established, the electromagnet 35 is now energized in any manner customary in the operation of metering devices. The energization of this magnet in actuating its armature permits the escape wheel 14 to be released one step in a backward or counter-clockwise direction. It will be apparent that the electromagnet 35 may be energized as many times as desired in accordance with 70 the established toll tariff for the services rendered until the stored calls have been exhausted, or in other words, until the sleeve 13 is restored to normal position, thereby opening contact springs 23 through the 80 agency of pin 22. When this occurs the subscriber's substation is open circuited, thus rendering it useless until another coin has been deposited.

From the above it will be apparent that a 85 plurality of calls may be stored for future use, depending upon the denomination of the coin or coins deposited. Also, that by adjusting the position of the pin 7 a discount or rebate may be given by purchasing 90 a given number of calls in advance, as for example, placing the pin 7 to be engaged by a dollar so that twenty-five calls are stored up upon the deposit thereof.

What is claimed is:

1. A coin collecting device including a ratchet mechanism, coin actuated means for advancing said ratchet mechanism, and means operated by a coin for restoring said ratchet advancing means to normal position. 100

2. A coin collecting device including a ratchet mechanism, means rendered effective by the introduction of a coin for advancing said ratchet mechanism, said means being manually operable, and means automatically operable by said coin for restoring said ratchet advancing means to normal position. 105

3. A coin collecting device including a ratchet mechanism, coin actuated means for advancing said ratchet mechanism, the advancement of said mechanism depending upon the denomination of the coin introduced, said means being manually operable, and means automatically operable for restoring said ratchet mechanism to normal position. 110 115

4. The combination with a subscriber's line terminating at a central office, of a coin collecting device including a ratchet mechanism, coin actuated means for advancing said ratchet mechanism, means for restoring said ratchet mechanism to normal position, and means for disabling the transmission circuit of said subscribers' lines, said disabling means being controlled by said ratchet mechanism. 120 125

5. The combination with a subscriber's line terminating at a central office, of a coin 130

collecting device including a ratchet mechanism, coin actuated means for advancing said ratchet mechanism, means for restoring said ratchet mechanism to normal position, and a pair of spring members for controlling the transmission circuit of said subscriber's line, said spring members being closed when said ratchet mechanism is in an

off-normal position and opened when said mechanism is in normal position.

In witness whereof, I hereunto subscribe my name this 22nd day of April A. D., 1916.

JACOB W. LATTIG.

In witness whereof, I hereunto subscribe my name this 7th day of April A. D., 1916.

CHARLES L. GOODRUM.
